CARBURETER.

1,159,167.

Specification of Letters Patent.

Patented Nov. 2, 1915.

Application filed October 3, 1912. Serial No. 723,666.

To all whom it may concern:

Be it known that I, GEORGE A. BREEZE, a subject of the Kingdom of Great Britain, residing at Detroit, in the county of Wayne, 5 State of Michigan, have invented certain new and useful Improvements in Carbureters; and I do declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates to carbureters for internal combustion engines, and consists in the construction and arrangement of parts hereinafter more fully set forth and pointed out particularly in the claims.

20 The primary object of the invention is to produce a carbureter wherein provision is made for automatically regulating the mixture as the throttle is opened and closed, and for obviating excessive feeding of liquid 25 fuel at high speed, while providing for a mixture of sufficient richness when the engine is throttled.

A further object is to provide a carbureter with a double feed atomizing tube having means for varying the richness of the 30 mixture delivered therethrough, and for feeding air with the fuel at both points of discharge.

The above objects are attained by the 35 structure illustrated in the accompanying drawings, in which:

Figure 1 is a vertical section through the main air and mixture passage in which the throttle is located and which leads to the 40 engine, the primary atomizing feed tube appearing in longitudinal section. Fig. 2 is a fragmentary view in section through a portion of the liquid fuel bowl or reservoir and through the primary atomizing feed tube, 45 said section being at right angles to that of Fig. 1. Fig. 3 is an enlarged longitudinal section through the secondary or auxiliary atomizing feed tube for slow and intermediate speeds. Fig. 4 is a cross-section as on line 4-4 of Fig. 3. Fig. 5 is an enlarged elevation of the primary atomizing feed tube. Fig. 6 is a sectional view as on line 55 6-6 of Fig. 5. Fig. 7 is an enlarged fragmentary view in transverse section through the cylindrical fitting in which the primary

atomizing tube is seated and the boss on the outer wall of the tube forming the main air and mixture passageway adapted to receive said fitting, the atomizing tube being omitted and the line of said section being indicated by dotted lines 7-7 of Fig. 1.

Referring to the drawings by the characters of reference marked thereon, 1 designates the main reservoir or bowl in which is located the usual float 2 for maintaining a 60 constant liquid fuel level, said float being connected to the pivoted arm 3 which actuates the valve 4 that controls the liquid fuel supply in a manner well understood in the art. The lower end of the valve 4 seats in 65 an aperture 5 in a fitting 6 with which the liquid fuel supply pipe, not shown, is adapted to be connected. Above the fitting 6 is a passage 7 communicating with the liquid fuel reservoir.

70 Rotatably seated in a projection 8 on the wall of the liquid fuel bowl or reservoir is the primary atomizing feed tube 9. This tube has a passageway 10 extending longitudinally therethrough which is contracted 75 at its longitudinal center and flaring at its ends. The outer end of the tube 9 has a shoulder 11 which engages the end of the projecting member 8 and regulates the distance which said tube may be introduced 80 into the aperture through said member. The inner end of the projecting member 8 through which the atomizing feed tube 9 passes is provided with a tubular extension 85 12 adapted to be seated in a boss 13 mounted 90 upon the exterior of the main air tube 14. The inner end of the tube 9 projects through the wall of the main air tube 14 and extends slightly into the contracted portion 15 of the main air passage 16 through the tube 14.

95 Communicating at its lower end with the liquid fuel space of the reservoir is a vertical liquid fuel passage 17, which, at its upper end, communicates with the horizontal opening through the projecting member 8 on the liquid fuel reservoir in which the tube 9 is seated. Formed diametrically through the wall of the tube 9 at the contracted portion of the passage therethrough are a number of apertures of different diameters designated by the numerals 18 to 21 100 respectively. These apertures are so disposed as to cause them to successively register with the upper end of the vertical passage 17 as the tube 9 is revolved. By 105 110

2

this arrangement, through a rotation of the tube 9, any one of the four jet or feed openings may be selected and placed in communication with the liquid fuel passage 17, therefore 5 by enabling the quantity of liquid fuel to be regulated to increase or decrease the richness of the mixture as may be desired in effecting a proper adjustment of the carbureter. The liquid fuel level in the reservoir 10 is slightly below the upper end of the passage 17 and liquid fuel is drawn from said passage into the tube 9 through the jet opening in said tube which registers with said passage by the inspirations of the engine, and flowing longitudinally through the 15 tube said liquid fuel is discharged from the inner end thereof into the contracted portion 15 of the air passage through the main tube 14. By extending the discharge end of the primary atomizing tube into the contracted portion of the air passage, a higher 20 velocity of air is obtained past the end of said tube thereby inducing greater suction therethrough without materially obstructing the main air passage. Said main tube at 25 its upper end is provided with the ears or flanges 22 for attachment to the intake port of the engine or to the carbureter manifold connected thereto. That portion of the passage through the tube 14 above the atomizer tube 9 becomes the mixture passage and located at a suitable point therein is the throttle valve 23.

When the engine is running at high speed 30 with the throttle open, the inspirations cause a rapid current of air to pass into the lower end of the tube 14, and also cause a strong current of air to flow through the atomizing tube 9. The rush of air through the tube 35 takes up the liquid fuel which enters said tube through the aperture therein communicating with the liquid fuel passage 17 and atomizes said liquid fuel, making a rich mixture which is discharged into the main air current passing through the tube 14, whereby a complete vaporization of the liquid fuel and its proper commingling with the inflowing air current is effected, producing an explosive mixture of high efficiency. 40 By making the passage 10 through the tube 9 tapered and causing the jet openings through said tube to communicate with said passage at the restricted point therein, the air passing through said tube is caused to 45 attain a high velocity at said point, producing a nebulizing effect upon the liquid fuel when passing over the jet opening through which the liquid fuel is being fed, whereby the liquid fuel is broken up into small particles and is partially mixed with the air which passes through the tube 9 before entering the main air current passing through the tube 15. On the projecting end 24 of the tube 9 are characters which correspond 50 with the jet apertures formed through the

wall of the tube and indicate which of said apertures is in communication with the liquid fuel passage 17, as shown in Fig. 5, wherein the numerals 18 indicate jet apertures in the tube and a corresponding designating character at the outer end thereof. To provide for arresting the tube 9 as it is rotated and yieldingly holding it in position so as to cause one of the feed jet apertures therein to register with the feed passage 17, there are provided in the outer face of said tube a plurality of sockets 25 which correspond with the feed jet apertures therein, and in which a ball 26 seated in the projecting member 8 is adapted to engage as said sockets are successively brought into registration therewith by rotation of said tube, said ball being pressed downwardly by a confined spring 27 engaging thereon. The ball drops into one of the recesses in the tube 9 when said tube shall have been rotated a proper distance to cause one of the feed jet apertures therein to register with the liquid fuel passage 17. The pressure of the spring downwardly upon the tube 9 causes it to seat firmly around its lower arc and prevents a possible leak of gasoline along said tube. 70

To provide for feeding an adequate mixture at slow speeds when the throttle is partially or entirely closed, a secondary mixture outlet is afforded through the medium of an upper atomizing tube 28 which is rotatably seated in an aperture formed laterally through the wall of the main air and mixture tube 14, the inner end of said tube 28 communicating with the interior of the tube 14 on a plane coincident with the edge of the throttle when said throttle is closed, as shown in Fig. 1. Formed through the wall of the atomizing tube 28 are a number of liquid fuel jet openings designated as 29, 30, 31 and 32. These jet openings by a rotation of the atomizing tube 28 may be made to successively register with the upper end of a vertical liquid fuel passage or by-pass 33 formed in the wall of the main tube 14. The lower end of the passage 33 communicates with the annular channel 34 (see Fig. 7) formed in the periphery of the tubular projection 12 through which the main atomizing tube 9 passes. Formed through the wall of the tubular projection 12 is a liquid fuel passage 35 also shown in Fig. 7, which connects the annular channel 34 with the interior of said tubular projection. The periphery of the main atomizing tube 9 is provided with a circular channel 36 shown more clearly in Fig. 5, which registers with the passage 35 and from which lead a number of apertures 37 into the opening through said atomizing tube. By this arrangement when the flow of air is partially or entirely cut off through the main tube 14 by a partial or a complete 75 80 85 90 95 100 105 110 115 120 125 130

closing of the throttle, the inspirations of the engine will create a strong suction at the inner end of the secondary atomizing tube 28, which suction will draw a mixture from the interior of the tube 9 through the apertures 37, the mixture passage 35, the vertical passage 33 and one of the jet openings in the tube 28 through said tube into the main air and mixture tube 14 at a point intermediate the discharge end of the primary tube and the engine intake, thereby supplying the requisite quantity of liquid fuel for slow speeds. To supply the required quantity of air to afford a proper mixture at slow speeds an air tube 38 is disposed within the secondary atomizing tube 28, as clearly shown in Fig. 3, which, at its outer end, is open to atmosphere, and through which air is drawn at a high velocity, thereby producing an atomizing effect upon the liquid fuel which enters the tube 28 through one of the jet openings therein and is entrained into the mixture portion of the main tube 14 with the air passing through the air tube 38. It has been found in practice that when running with the throttle closed so as to effect a strong suction at the inner end of the tube 28, additional air will be drawn into the flaring inner end of the main atomizing tube 9 which will pass upwardly with the liquid fuel through the liquid fuel passage 33, thereby assisting in effecting a perfect commingling of the liquid fuel and air and affording a proper mixture for the engine at slow speeds.

It will be noted that as the throttle is gradually opened from the position shown in Fig. 1, the suction upon the secondary atomizing tube 28 will gradually decrease, and the suction upon the main atomizing tube 9 will gradually increase until the feed will be cut off from the secondary tube 28 and will be wholly through the main tube 9. It will be apparent that as the throttle closes the feed through the tube 9 will gradually decrease and at a certain position of the throttle will commence through tube 28 until the feed through tube 9 will entirely cease and the engine will be supplied with mixture entirely through the secondary tube via the primary tube. These changes are effected without a material change in the character of the mixture which remains practically constant owing to the provision for regulating the supply of liquid fuel and air in a manner to compensate for the changes in the position of the throttle.

It will be noted that the air tube 38 through which air is drawn into the secondary atomizing tube 28 projects from the end of a threaded plug 39 which is adapted to screw into the outer end of the tube 28. This arrangement renders said air tube detachable and enables the volume of air to be regulated by removing one tube and sub-

stituting another of greater or lesser diameter as conditions may require. This variation in the air supply is compensated for by varying the supply of liquid fuel through a rotation of the tube 28 to bring into operation a jet aperture of greater or lesser area as may be required. By this means of regulating the mixture supply through the secondary atomizing tube by controlling the volume of admitted air, excessive richness of the mixture is obviated, and the liquid fuel is prevented from flowing out of the forward end of the atomizing tube and down the main air intake when the engine is throttled very slow.

The auxiliary or secondary atomizing tube 28 is rotatably held in place through the medium of a ball 40 which finds a seat in the uppermost of the jet openings in said tube, and is held under tension by a spring 41 which bears upon said ball. This method of mounting the tube 28 enables it to be readily withdrawn for the purpose of cleaning the jet openings therein should they become clogged with dirt. The primary atomizing tube 9 may also be withdrawn in a like manner for the same purpose should it become necessary. Adjustments are ordinarily made by rotating the primary atomizing tube to select the proper jet opening for high speed and revolving the secondary atomizing tube to select the proper jet opening when the engine is throttled down.

The connection between the main air and mixture tube 14 and the bowl or reservoir is such that the main air tube may be placed in either the vertical or horizontal position, as desired.

The cover 42 of the bowl or reservoir is hinged on the screw 43 which also engages a spring tension arm 44 that bears upon said cover and holds it yieldingly in place.

It will be noted that by the arrangement herein shown the main air passage is unobstructed, insuring the requisite volume of air at high speeds.

Having thus fully set forth my invention what I claim as new, and desire to secure by Letters Patent, is:

1. A carburetor, having a main air and mixture passage, a primary atomizing tube communicating with said passage and also with the atmosphere, a source of liquid fuel supply communicating with said primary tube at an intermediate point thereof, the tube being adjustable to vary its supply from said source, a secondary mixture tube, communicating with the primary tube, between its points of communication with the main passage and the fuel supply, and having an outlet to the main passage, means for varying the discharge from said outlet, and means in the main passage for varying the pressure at the points of communication of said tubes with said passage.

2. A carbureter having a main air and mixture passage, an atomizing tube communicating therewith and with the source of liquid fuel supply, said tube having selective liquid fuel jet openings of different areas, and means for affording a constant air supply to said atomizing tube.
3. A carbureter having a main air and mixture passage, a source of liquid fuel supply, an atomizing tube rotatably mounted communicating with said passage and having variable liquid fuel feed openings arranged for independent communication with said source of liquid fuel supply, and means for affording a flow of air through said atomizing tube.
4. In a carbureter, a rotatable feed tube having a central air passage therethrough, and a plurality of liquid fuel passages in the wall thereof communicating with said air passage and adapted for independent communication with a source of liquid fuel supply.
5. A carbureter having a feed tube with a restricted air passage extending longitudinally therethrough, the wall of said tube having a plurality of liquid fuel openings of different areas communicating with said passage at its restricted point, and a source of liquid fuel supply with which said liquid
- fuel openings may be caused to independently register.
6. In a carbureter having a main air and mixture passage, a primary atomizing tube communicating with said passage and with a combined source of air and liquid fuel supply, variable feed openings in said tube for regulating the quantity of liquid fuel, a secondary atomizing tube fed from said primary tube and also communicating with said passage, said secondary tube having variable feed mixture openings, and means for selecting any of said openings at will.
7. A carbureter having a main air and mixture passage, a primary mixture tube communicating with said passage and also with the atmosphere, a source of liquid fuel supply communicating with said tube at a point above the normal level of the liquid fuel, a secondary mixture tube communicating with said primary tube, and with said main passage, and means in the main passage for varying the pressure at the points of communication of said tubes therewith.
- In testimony whereof, I sign this specification in the presence of two witnesses.
- GEORGE A. BREEZE.
